UNITED STATES PATENT OFFICE

PAUL WOLF, OF ZWICKAU, GERMANY

ELECTRIC ACCUMULATOR

Application filed April 28, 1930. Serial No. 448,063.

This invention relates to accumulators, more particularly for operating miner's lamps, and to comparatively easily portable accumulators of elongated rectangular cross-section, which are used for supplying current to head lamps (incandescent lamps carried on the cap of the miner). The object of the invention is in general to increase safety in operation and avoid danger from fire damp. For such accumulators an absolutely tight and reliable closing of the accumulator vessel is of particular importance, because the conductors and fittings on the cover of the accumulator vessel would be damaged by a leakage of the electrolyte. In accumulators of elongated-flat shape, leaks may easily occur if the cover, in the shape of a long narrow rectangle, is not everywhere strongly and uniformly pressed on. Such a uniform pressing on is made possible by the lever arrangement to be described, in which also provision is made for the quickest and most convenient manipulation of the closing cover.

It is known to provide two-armed closing levers which are adapted to move about a pivot mounted on the cover and which are operated by means of a screw, which is arranged in the middle of the cover and engages a bridge member connecting the ends of the levers. These systems are however not applicable for elongated covers and especially for such covers which are made of hard rubber or the like because they exert tension and pressure on the cover and also actually cause a deformation of the cover if the latter does not consist of resistible material.

Figure 1 of the accompanying drawing illustrates such an accumulator, being an elevation of the narrow side, with a partial cross section.

Figure 2 is a front elevation, with a partial section through the accumulator vessel and cover, so that the inner parts and arrangements are visible.

Figure 3 is a plan view of the accumulator, the outer cover 4 with the parts attached thereto being removed.

The elongated rectangular vessel 1 contains two cells 33 with pairs of electrodes 14—14 which are attached to the cover 2 by holders

12. The cells are closed by the cover 2 supported on a rubber ring 10, which is pressed on as is described below. The pieces 6 and 15 are fixed (welded, soldered) to the vessel 1 and have slots at their upper ends. The pieces 15 are extended at the lower ends and are so shaped that a belt for carrying the vessel may be passed through. The pins 27 attached to the frame-like levers 3 are pushed into the above mentioned slots of the pieces 6 and 15, so that the levers may be moved about these pins as fulcrums. The two levers are connected together at the middle of the vessel by a bridge member 29 so as to be angularly movable. The bridge member 29 contains the screw thread for the pressure screw 28, which presses on the pressure piece 30 which covers almost the whole width of the accumulator. By turning the screw the bridge member 29 and with it the inner arms 60 of the levers 3 may be lifted. The outer lever arms then lie against the cover 2 and exercise a pressure on this simultaneously with the part 30. It is thus possible to exercise a pressure at the middle of the cover 2, and at the same time on its ends, by means of this single screw 28, whereby the pressure is well distributed by the broad pressure piece 30 and the cross pieces of the frame 65 70 75 80 85 90 95 100 3. To open the accumulator vessel, it is only necessary to loosen the screw 28 and to slide the lever 3, now lying loose, with its pins 27, to the left out of the slots of the pieces 6 and 15. The closing parts 3, 29, 30, 28 form a joint system movable within itself.

The parts 12 nearest to the narrow side of the vessel which are pressed or cast into the cover 2 consisting of insulating material, form at the top contact blades which lie between the contact springs 20 and 22 on the outer cover 4. Further, bushes 11 are fixed to the cover 2 which form the apertures for filling the cells with electrolyte. The stoppers screwed into these bushes and tightly closed with rubber rings are formed as dipping contacts for testing the height of the electrolyte, and are reached by the electrolyte when a sufficient quantity of it is present. At the upper ends the stoppers 13 are elongated so that they reach through openings in the

outer cover 4. It can thus be ascertained, whether the electrolyte in a cell stands at a sufficient height, by applying a current circuit consisting of an accumulator 31 and lamp 32 to the dipping conductor and to the outer wall of the accumulator vessel, in the manner shown in Figure 2, when the lamp 32 should light up, if the liquid level is correct. It is, however, impossible for unauthorized persons to remove the stoppers 13, as they are cut away at their upper ends, and are held fast in the rubber rings 17, 18 fitted in the apertures of the cover 4. On the other hand the cover 4 cannot be fitted on and closed if the stoppers 13 are not properly screwed in. The completely removable cover 4 is so formed that it overlaps the edge of the accumulator vessel 1 on all four sides. It thereby engages, with its strengthened hook-like extension 4a (Figure 2, left), the protruding edge of the vessel, while on the opposite side (Figure 2, right) it is secured by the hasp of the flap 8 which is rotatable in the joint 7, and whose nose 8a enters a hole in the cover. The nose 8a is secured to the cover by a latch 9 under spring pressure, which can only be released by means of a strong magnet. The rings 17, 18 in the cover 4 thus serve for various purposes. They prevent the closing of the cover 4 when the stoppers 13 are not properly screwed in; they close tightly the openings in the cover 4 about the stoppers 13; they insulate the stoppers from the cover.

Inside the cover 4 are the contact springs 20, 22 which are fixed by the screws 19 and 21. From the screw 21 a conductor 26 leads directly to the outgoing cable 5; from the screw 19 the current passes through a fuse 23 to the screw 24 and from there to the conductor 25 and into the cable 5. A lamp attached to the other end of the cable 5, e. g. a head lamp can now be so secured that in case of damage a short circuit is caused so that the fuse 23 melts and the conductors 25, 26 carry no more current. When the accumulator is quite ready for use and properly closed, it is impossible either to damage an important part of it, or to touch any current carrying conductor, and it is also possible to test easily whether a sufficient amount of electrolyte is present in the cells without having to remove the cover 4.

What I claim is:

1. An accumulator comprising a vessel, a cover for the vessel, two-armed levers arranged thereon which levers are rotatable about fixed points on the accumulator vessel and a pressure screw which presses on the cover for pressing one arm of each of the levers away from the cover, whereby the other arms of the levers press on the cover, and the cover is pressed on simultaneously by the screw in the middle, and by the levers at the ends.

2. An accumulator as claimed in claim 1, having a broad pressure piece which distributes the screw pressure over almost all the middle of the cover.

3. An accumulator as claimed in claim 1, in which the levers are so formed that they press on almost the whole width of the cover.

4. An accumulator as claimed in claim 1, comprising a bridge member having a screw threaded hole, and engaging with the nearer arms of the levers and the pressure screw passing through the said screw threaded hole.

5. An accumulator as claimed in claim 1, having a bridge member which engages with the lever arms in such a manner that the system comprising the two levers, the pressure screw and the bridge member forms a single unit when detached from the cover.

6. An accumulator as claimed in claim 1, in which the levers have pins attached thereto in combination with hook-like parts on the accumulator vessel which have slots, in which slots the said pins are inserted.

In testimony whereof I have signed my name to this specification.

PAUL WOLF.
